3 Claims. (Cl. 237—1)

This invention relates to methods of operating a heat exchange system utilizing a circulating stream of liquid in a closed loop which includes both a heat-addition zone and one or more heat-withdrawal zones, and particularly refers to methods of stabilizing and controlling the operation of such systems which utilize specific properties of the liquid medium employed at pressures and temperatures approaching its critical point.

Certain endothermic chemical reactions involving organic materials which are carried out in confined zones or reactors at pressures varying up to about 3000 p.s.i.a. (pounds per square inch, absolute) and at temperatures ranging up to about 700° F., require very accurate control of both the temperature and pressure of the reaction zone to obtain safe and economical stable operation. An example is that of U.S. Patent 2,722,549, entitled, "Oxidation Process," for producing phthalic acids from hydrocarbons. Physical limitations of structural materials used to confine such reaction zones include tensile strength properties, resistance to corrosion at the conditions encountered, reactivity of reacting materials with heating fluids in case of equipment leaks or failure, and other factors known in the chemical processing art. To add the heat required for the endothermic reaction, to preheat the reacting materials, to compensate for heat losses, etc., it is contemplated to provide a confined stream of circulating fluid in a closed loop, one part of which may be a tubular furnace for adding heat, and another part of which may be one or more tubular heat exchangers or reactors of suitable construction. Circulation is established by appropriate pumps, usually of the centrifugal type.

Heretofore, liquid media for heat transfer under temperature conditions above about 450° F. have been petroleum oil fractions at atmospheric pressure for ranges from 300° F. to about 550–600° F., above which coking occurs. Other liquids, such as "Dowtherm," ordinarily used as the eutectic mixture of 73.5% diphenyl oxide and 26.5% diphenyl, are usable as a liquid up to 500° F. at atmospheric pressure and as a vapor up to 100 p.s.i.g. and 700° F. Molten salts and molten metals, e.g., NaK eutectic, have been used, but are hazardous if there is any possibility of leakage to atmosphere or to an aqueous reagent.

The present invention is exemplified in this specification as applied to ordinary water, which, under the desired conditions of use, 600°–700° F. and 3000–3200 p.s.i.a., is near its critical point. The unexpected advantages of this liquid under these conditions to function in a controlled, stable, heat-exchange system will be discussed in detail below in connection with the novel combination of steps and apparatus that are employed. These steps include the provision of a circulating mass of water in a closed system comprising a heat-addition zone and one or more heat-withdrawal zones, with provision for controlling the temperature in the last-named zones by adding water at a constant rate to the circulating mass and withdrawing a variable quantity, depending upon the temperature to be maintained. Additional tempera-

2

ture control may be imposed by adding heat to the heat-addition zone at a rate controlled by the outlet temperature of the water leaving that zone. Also, the temperature profile across the several heat withdrawal zones may be controlled by regulating the flow paths of the circulating fluid.

A specific application of this method that will be described below is to a liquid-phase hydrocarbon oxidation process in which heat is to be added to the incoming reactants prior to their introduction into a series of reaction zones, and also is supplied in varying amounts to the last-named zones to maintain the temperature and temperature profile of the endothermic reaction therein at the optimum value. Liquid make-up to the circulating system and the inevitable heat losses make up the remainder of the heat load. The reaction conditions are such that the temperature is desirably maintained within the relatively narrow range of about 620°–640° F., and the pressure is kept above about 2800 p.s.i.a. to prevent reactant vaporization as well as vaporization of the heating liquid. The nature of the reactants and the materials of the tubular heat exchangers in which the reaction occurs desirably are such that any failure or leakage should be from the heating liquid side to the reactant side, and not in the opposite direction. Thus, the pressure on the heating liquid side must exceed 2800 p.s.i.a., and has been chosen, in this example, to be in the range from about 3000–3200 p.s.i.a. Under these conditions, the properties of ordinary fresh water, which have been found suitable for the system in question, are quite different from those usually encountered at lower pressures and temperatures, and are illustrated graphically in certain of the drawings herein. Aqueous solutions generally would have comparable properties and may be of advantage in certain applications of the methods of the invention.

This invention will be more clearly understood if it is considered that essentially three systems are involved: the process reactor system, which is at a controlled pressure determined by the reaction conditions therein; a circulating heating water system, which is not held at any fixed value, but is controlled to a value about 200 p.s.i. above the reactor system; and a water make-up system or water source. Regarding the make-up water source as a system, it is held by means of a suitable pump and pressure controller to a value about 50 p.s.i. above the circulating water system.

Referring now to the pressure conditions for the circulating water system, it is controlled by bleeding or removing water from that system at the rate required to hold the total volume of water constant. The difference between volume and mass of water should be kept in mind relative to their effect on system pressure, since the effect of changing temperature level within the system and changing temperature profile around the system is to destroy any fixed relationship between the mass of water in the system and the pressure resulting therefrom. For example, when the system is cold, density of the water is high (specific gravity about 1.0) and a relatively large mass of water is required to fill the system and "squeeze" against the containing piping and vessels to raise pressure to the desired value. As the temperature rises, for example, to a value near its critical point, the density decreases rapidly, causing a smaller mass of water to occupy the same volume. Therefore, water must be removed from the system to maintain the same pressure. Conversely, if the temperature in the system as a whole, or any part of it, is lowered, water must be added to maintain the system pressure.

Temperature-density relationships of water at this temperature level are such that large changes in rate of addition of cold water would seriously affect the tem-

perature profile within the system, and therefore correspondingly affect the pressure. To overcome this, water is added at a constant rate, establishing a constant heat demand which is supplied by the heating zone. Water is bled from the system at a greater or smaller rate as is required by the pressure conditions. Thus, the total mass within the circulating system is controlled by the difference between the constant rate of addition of cold water and the varying rate of withdrawal of hot water.

It is an object of this invention to provide a method of stabilizing the operation of a heat-transferring system using a liquid medium, for example, water or an aqueous solution, under conditions approaching its critical point.

Another object is to provide a method of supplying heat at an accurately controlled rate to an endothermic process in which deviations from normal conditions of operating are self-correcting or at least occur so slowly that a supplementary automatic or manual control may be imposed to attain and maintain equilibrium in both pressure and temperature.

Another object is to provide a method of operating a closed system for heat interchange in a chemical process with substantially a constant mass of circulating liquid, and desirably water, in the system so that changes in temperature of the heat-withdrawal zone are reflected by substantial changes in the system pressure, which changes may be used to restore the system to the desired operating conditions.

Another object is to provide a method of controlling the pressure in a closed system carrying a circulating liquid that passes successively through a heat-addition zone and one or more heat-withdrawal zones by adding liquid to the system at a constant rate and withdrawing liquid at a variable rate, depending upon pressure changes in the system.

These and other objects and advantages will be further apparent from the following description of a preferred and an alternative embodiment of a system for carrying out the steps of this invention, taken in connection with the attached drawings, which form a part of this specification.

In the drawings:

Figure 1 is a curve showing relationship between pressure, temperature, and mass of water in a circulating system of a given size, in this case, containing 600 cubic feet.

Figure 2 is a similar curve showing a part of the data of Figure 1, to an enlarged scale.

Figure 3 is a simplified flow diagram of a system embodying this invention and adapted to supply heat to a reaction zone.

Figure 4 is a simplified flow diagram of an alternative form of a system embodying this invention and adapted to supply varying quantities of heat to a plurality of heat-withdrawal zones.

Referring to the drawings, and particularly to Figures 1 and 2, the family of curves there shown illustrates the essential relationships between pressure, temperature, and the mass of a water-filled closed system, in this case having an arbitrary constant volume of 600 cubic feet, under conditions approaching the critical point for water. The ordinate scale represents the mass of water in the system and the abscissa scale represents the pressure in the system. It will be noted that, for a temperature increase, for example, from 600° F. to 620° F. at a controlled pressure of 3400 p.s.i.a., about 900 pounds of water must be released from the system. Such a condition may be encountered by a change in the process conditions of the reaction to which heat is being added by the circulating water system of this example. Conversely, if the heat demand should decrease, or if a change in temperature profile in the several reactors should require a comparable decrease in average system temperature, 900 pounds of water would be required to be added to maintain the desired pressure and temperature conditions.

Figure 1 shows the relationships just discussed for a temperature range from 100° F. to 700° F. Figure 2 is a portion of the same set of curves, but to an enlarged scale and in the more limited range of 640° to 700° F.

5 Lines A and B illustrate a desired range of pressure conditions for the exemplary system of this specification.

Referring now to Figure 3, which illustrates schematically a very simple embodiment of the invention, reference numeral 10 designates a heat-addition zone, which 10 may be a tubular or other type of furnace, with a burner 11 supplied by a fuel line 12 provided with a regulator 13 controlled by the temperature of the water leaving zone 10 through outlet line 14. Line 14 leads to a heat-withdrawal zone 15 which may be one or more indirect 15 heat-exchangers or reactors with appropriate lines 16 and 17 to carry reactant fluids into and out of the zone. An example of the type of reaction zone to which this invention is particularly adapted is that of U.S. Patent 2,722,549, issued November 1, 1955, to W. G. Toland, 20 Jr., on an "Oxidation Process."

From the heat-withdrawal zone 15, line 18 carries the 25 circulating water stream to circulating pump 19, from which it returns to the heating zone 10 through line 20. Desirably, a flow rate controller 21 admits water through 25 line 22 to the system at a constant rate from any suitable source (not shown), which is under a pressure greater than in that part of the system. When changes in process requirements or other variables modify the average 30 temperature of water in the system, thus requiring a change in the mass of water therein as discussed above and illustrated in Figures 1 and 2, a pressure-controlled regulator 23 in water outlet line 24 controllably carries out the desired release of water at a variable rate, as will be apparent to one skilled in this art.

35 In practice, this system has been found to be directionally stable due to the mass of water in the circulating stream and the heat capacity of the heat-withdrawal equipment and the fluid reactants therein, as well as to the novel method for regulating the mass of water in the 40 closed system.

Reference is now made to Figure 4, which illustrates a more complex embodiment of the invention, including 45 temperature-, flow-, and pressure-control means for adjusting the temperature gradient in a plurality of heat-withdrawal zones, certain groups of which may have somewhat different heat demands. Another characteristic of this arrangement, which will be further apparent from the detailed description below, is the step of storing at a lower pressure the water that is variably 50 withdrawn from the circulating system, and reusing it for making up the constant rate water input. Similar reference numerals have been employed where they are applicable.

In Figure 4, the heat addition zone 10 is illustrated 55 as a tubular heater with burners 11 supplied by fuel from any suitable source (not shown) through line 12 and regulated by valve 13 which is responsive to the temperature of water leaving zone 10 through outlet line 14. That line is branched at 30 so as to provide 60 controlled parallel flow of water through tubular heat exchangers 15a and 15b, and provision is also made by a connection 31 and a flow regulator 32 to by-pass a portion of water leaving exchanger 15a to pass through a reactant preheater 33 and thence through a temperature-responsive regulator 34 to line 18, so that the reactant feed entering through line 16 will be heated to a predetermined temperature before it reaches heat-exchanger 15a. Also, a by-pass line 35 with a pressure 65 differential controller 351 may be included to further afford accurate control of temperature gradients in the heat exchangers 15a, b, c, and d.

The step of storing the water which is withdrawn 70 from the system at a variable rate dependent upon the temperature-pressure-mass relationships mentioned above, and returning it to the system at a constant rate is car-

ried out, in this example, by means of an appropriately dimensioned surge drum 36, the inlet of which communicates with the circulating water line 18 by means of line 24, part of which desirably forms a heat-exchange coil 37 in drum 36, and a pressure-responsive flow regulator 23. Desirably, that regulator is responsive to the pressure in the water circulating system and is also arranged to be reset as required by the pressure in the reactant feed inlet line 16 so as to maintain a constant excess of pressure in the circulating water system, for example, 100 to 200 p.s.i. above the pressure in the reactant system. As mentioned above, this insures that any leakage will be from the water to the reactant system, and not in the opposite direction.

It will be apparent, from a consideration of Figures 1 and 2, that surge drum 36 will be required to accommodate a substantial change in liquid level due to water that must be bled off from the circulation system during starting periods and replaced when shutting down, so that a plurality of vertically spaced liquid level controls generally designated 38 are usually required selectively to control water level in that drum. Absolute pressure of about 20 p.s.i.a. in drum 36, in this example, is provided by a vent condensing coil 39 in the top of the drum, supplied by cold water and regulated by pressure controller 40. A valved vent outlet 41 bleeds air and uncondensed gas continuously from the top of the condensing section.

One of the unique features of the circulating pump 19, which operates at pressures of 3000-3400 p.s.i.a. and temperatures up to about 690° F., is the provision for sealing against leakage the shaft 42 connecting the pump and its prime mover generally designated 43. Conventional packings between the shaft and pump housing are not usable under the pressure and temperature conditions just outlined, and the sealing requirement for the shaft 42 is met by providing flow-throttling means, in this case an elongated sleeve 44 having a plurality of successive close-clearance annular constrictions or diaphragms therein, in the manner of a steam turbine shaft labyrinth, with a water inlet connection 45 at the inner end of the labyrinth and a water outlet connection 46 at its outer end. Water from surge chamber 36 passes through outlet line 47 and high pressure make-up pump 48 to a flow-regulator 21 from which it divides at 49, so that part of the flow passes through line 22 to the main water circulating line 20, and the remainder passes through branch line 50 to the sealing water inlet connection 45 of circulating pump 19. Here again the water flow divides, part passing into the body of pump 19 and the remainder passing through the shaft-sealing labyrinth to the outlet connection 46 and thence through the valved water return line 51 to the low-pressure surge drum 36. Desirably, a differential pressure regulator 52 is provided to control the division of water between line 22, leading to the main circulating stream, and line 50, leading to the circulating pump sealing inlet 46, by returning the excess from make-up pump 48 to surge chamber 36.

The methods and means described have been quite successful in meeting the requirements of the exemplary system, which uses fresh water under conditions approaching the critical point (3226 p.s.i.a. and 706° F.) by providing for the large changes in density of the water with temperature. The high pressure circulating water system has a substantially fixed volume determined by the several components of the heat-addition zone, heat-withdrawal zone, circulating pump and lines,

so that the mass of water therein must vary with both the average water temperature and the temperature profile in the system. This is accomplished by pumping into the system a constant surplus of water and at the same time withdrawing a variable amount dependent on the pressure conditions in the water system and also in the reaction system. Ancillary means for controlling temperature gradient in a plurality of heat-withdrawal zones includes flow controls and pressure-controlled bypasses as described above.

From the foregoing, it will be apparent that an easily balanced and inherently stable flow- and temperature-regulating system has been provided, as has been proved in operation, to carry out the method of this invention, as defined in the following claims. Although only specific embodiments have been illustrated and described in detail, it will be apparent that changes can be made without departing from the essential features of the invention. Accordingly, all such modifications as are covered by the appended claims are intended to be included therein.

We claim:

1. A method for transferring heat which comprises circulating a liquid at a temperature substantially above its normal boiling point and under a high superatmospheric pressure through a closed loop system including a heat input zone and a heat withdrawal zone in which heat is transferred from the liquid circulating in the loop, introducing liquid into the loop at a substantially constant rate and withdrawing liquid from the loop at a point in the loop removed from the point of liquid introduction at a variable rate adapted to maintain a predetermined high superatmospheric pressure in the loop.

2. A method for transferring heat which comprises circulating a liquid at a temperature approaching its critical temperature and under a high superatmospheric pressure through a closed loop system including a heat input zone and a heat withdrawal zone in which heat is transferred from the liquid circulating in the loop, introducing liquid into the loop at a substantially constant rate and withdrawing liquid from the loop at a point in the loop removed from the point of liquid introduction at a variable rate adapted to maintain a predetermined high superatmospheric pressure in the loop.

3. A method for transferring heat which comprises circulating water at a temperature above about 600° F. and at pressures above about 2800 p.s.i.a. through a closed loop system including a heat input zone and a heat withdrawal zone in which heat is transferred from the water circulating in the loop, introducing water into the loop at a substantially constant rate and withdrawing water from the loop at a point in the loop removed from the point of water introduction at a variable rate adapted to maintain a predetermined pressure above about 2800 p.s.i.a. in the loop.
